US0D1046029S

(12) **United States Design Patent** (10) **Patent No.:** **US D1,046,029 S**
(45) **Date of Patent:** **** Oct. 8, 2024**

(54) **FITNESS EQUIPMENT**

(71) Applicant: **Ningbo Ainfox Network Technology Co., Ltd.**, Ningbo (CN)

(72) Inventors: **Shaofeng Gao**, Ningbo (CN); **Xiong Jiang**, Ningbo (CN)

(73) Assignee: **Ningbo Ainfox Network Technology Co., Ltd.**, Ningbo (CN)

(**) Term: **15 Years**

(21) Appl. No.: **29/855,122**

(22) Filed: **Sep. 30, 2022**

(51) LOC (14) Cl. **21-02**

(52) U.S. Cl. **D21/686**; D21/662; D21/673; D21/679; D21/691

(58) **Field of Classification Search**

USPC D21/662, 673, 675, 677, 679, 680, 682, D21/686, 691, 696

(57) **CLAIM**

The ornamental design for a fitness equipment, as shown and described.

DESCRIPTION

FIG. 1 is a first perspective view of a fitness equipment showing our new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the selected portion 9 in FIG. 1; and,

FIG. 10 is an enlarged view of the selected portion 10 in FIG. 2.

The dash-dash broken lines show portions of the fitness equipment that form no part of the claimed design. The dash-dot broken lines in FIGS. 1-2 and 9-10 depict the bounds of the detail views and form no part of the claimed design.

1 Claim, 10 Drawing Sheets
